US0D1004164S

(12) United States Design Patent (10) Patent No.: US D1,004,164 S
(45) Date of Patent: * Nov. 7, 2023

(54) LIGHT

(71) Applicant: Xiaofang Zhou, Linhai (CN)

(72) Inventor: Xiaofang Zhou, Linhai (CN)

() Term: 15 Years

(21) Appl. No.: 29/819,769

(22) Filed: Dec. 17, 2021

(51) LOC (14) Cl. 26-04

(52) U.S. Cl.

USPC D26/25; D11/121

(58) Field of Classification Search

USPC D26/2, 25, 27, 51, 60–61, 72–73, 81, 88, D26/118; D11/117, 119, 121, 124, 125

CPC F21S 4/00; F21S 4/10; F21S 4/15; F21W 2121/00; F21W 2121/004; F21W 2121/04

Assistant Examiner — Melissa Adriane Santos

(57) CLAIM

The ornamental design for a light, as shown and described.

DESCRIPTION

FIG. 1 is a perspective view of a first embodiment of a light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the light;

FIG. 10 is a perspective view of a third embodiment of the light;

FIG. 11 is a perspective view of a fourth embodiment of the light;

FIG. 12 is a perspective view of a fifth embodiment of the light; and,

FIG. 13 is an enlarged view of portion 13 shown in FIG. 2. The dash-dash broken lines in the drawings depict portions of the light that form no part of the claimed design. The dot-dash broken lines represent boundaries of the enlarged portions and form no part of the claimed design.

1 Claim, 13 Drawing Sheets
